DESIGN FOR A BAKING DISH OR SIMILAR ARTICLE

Arthur P. Miller, New Kensington, Pa., assignor to
The Aluminum Cooking Utensil Company, New
Kensington, Pa., a corporation of Pennsylvania

Application June 24, 1941, Serial No. 101,639

Term of patent 7 years

To all whom it may concern:

Be it known that I, Arthur P. Miller, a citizen of the United States, residing at New Kensington, in the county of Westmoreland and State of Pennsylvania, have invented a new, original, and ornamental Design for a Baking Dish or Similar Article, of which the following is a specification, reference being had to the accompanying drawing, forming a part thereof, in which:

Fig. 1 is a view partially in elevation and partially in section; and

Fig. 2 is a bottom plan view of a baking dish or similar article, showing my new design.

The material of the baking dish is transparent, with translucent stippled areas indicated by shaded portions in the drawing.

I claim:

The ornamental design for a baking dish or similar article, substantially as shown and described.

ARTHUR P. MILLER.
